UNITED STATES PATENT OFFICE.

McROY DE VIESE, OF FRESNO, CALIFORNIA.

TRACTION-ENGINE.

1,051,201.

Specification of Letters Patent. Patented Jan. 21, 1913.

Application filed April 22, 1912. Serial No. 692,449.

To all whom it may concern:

Be it known that I, McROY DE VIESE, a citizen of the United States, residing at Fresno, in the county of Fresno and State 5 of California, have invented a new and useful Traction-Engine, of which the following is a specification.

This invention relates to plows and is more particularly an improvement upon the 10 structure disclosed in an application filed by me on September 14, 1911, said application bearing Serial No. 649,301.

One of the objects of the invention is to provide improved means whereby motive 15 power may be transmitted to all of the supporting wheels of the structure, thereby increasing the tractive force of the machine.

A further object is to provide improved means for transmitting motion from a single 20 motor to the traction wheels and to the rotary plows used in connection with the machine.

A further object is to provide improved means for steering the machine during the 25 transmission of power to the steering wheels.

With the foregoing and other objects in view which will appear as the description proceeds, the invention resides in the combination and arrangement of parts and in 30 the details of construction hereinafter described and claimed, it being understood that changes in the precise embodiment of the invention herein disclosed can be made within the scope of what is claimed, without departing from the spirit of the invention.

In the accompanying drawings the preferred form of the invention has been shown.

In said drawings:—Figure 1 is a plan 40 view of a plow having the present improvements combined therewith. Fig. 2 is a longitudinal section through the machine. Fig. 3 is a view partly in front elevation and partly in section of a portion of the machine.

45 Referring to the figures by characters of reference 1 designates the frame of the machine having a supplemental frame 2 mounted in the rear portion thereof and adapted to swing about a transverse shaft 3 as an axis, said supplemental frame carrying a central shaft section 4 connected, by universal joints 5, to side shaft sections 6, all of said sections carrying rotary plows 7 of any preferred type. A bell crank lever 50 8 or the like is mounted on the rear portion of the main frame 1 and is connected, as

by means of a link 9 to the supplemental frame 2, there being any suitable mechanism, such as a rod 10 and a lever 11 for actuating the bell crank lever 8 so as to shift the supplemental frame 2 and thereby raise or lower the rotary plows as desired. The shaft sections 6 can be swung relative to the central section 4 so as to bring the rotary plows on said section in any desired positions relative to each other. The mechanism employed for adjusting these sections can be of any desired construction and inasmuch as it constitutes no part of the present invention it is not deemed necessary to 70 enter into a detailed explanation thereof.

Shaft 3 is preferably formed in two sections connected by a differential indicated generally at 12 said differential including an external gear 13 receiving motion 75 through a gear 14 from a longitudinally extending shaft 15 which is journaled on the main frame 1 and is connected, as by means of a universal joint 16, to a shaft 17 which, in turn, receives motion through a chain 18 and sprockets 19 and 20, from a motor 21 mounted on a platform 22 arranged preferably on the front portion of the frame 1. A stationary arched axle 23 extends transversely of the rear portion of frame 1 and has traction wheels 24 mounted for rotation 80 on the end portions thereof, each of these traction wheels being provided with a sprocket 25 secured thereto and revoluble therewith. Each sprocket wheel receives 85 motion, through a chain 26, from a sprocket wheel 27 secured to one end of the shaft 3. A sprocket 28 is secured to one of the shaft sections 3 and a motion is transmitted therefrom, through a chain 29, to a sprocket 30 secured to the middle section 4 of the shaft of the rotary plow. Thus it will be seen that when shaft 3 is rotated motion will be transmitted therefrom to the rotary plows and also to the two wheels 24 and, by providing the differential 12, said wheels 24 are permitted to rotate at different speeds as when the machine is turning.

The front or steering axle 31 contains a shaft 31' which is adapted to rotate and is 95 made up of two sections connected by a differential indicated generally at 32. The front traction wheels 33 rotate with the sections of shaft 31' and said shaft sections are mounted within and are adapted to shift 100 35 at the top thereof. A shaft section 36 is

journalized within the yoke and it projects into extension 35, the lower end of said shaft section being provided with a gear 37 which meshes with the external gear 38 of the differential 32.

5 A bearing member 39 is mounted within the extension 35 and has a stem 40 projecting upwardly therefrom and fixedly connected to the front portion of the main 10 frame 1. A shaft section 41 is journalized within the stem 40 and is connected to the section 36 by a universal joint 42. The upper end of the shaft section 41 has a gear 43 meshing with another gear 44 which is secured to a shaft 45. This shaft is adapted 15 to receive motion from the shaft 17 through a chain 46 and sprockets 47 and 48.

From the foregoing it will be seen that motion can be transmitted from the motor 20 21 to the front shaft 31 irrespective of the angle to which the main frame 1 may be shifted relative to the front axle 31 and also irrespective of the horizontal angular adjustment of the front axle.

25 For the purpose of reinforcing the connection between the front axle and the main frame, an extension 49 extends forwardly from the yoke 34 and its front end is adapted to travel within an arcuate guide 50 connected to the front end portion of the main 30 frame 1. Another extension 51 extends rearwardly from the axle and is adapted to travel within an arcuate guide 52 connected to the main frame 1. The steering chains or cables 53 are connected to this extension 35 51 and extend laterally into engagement with guide sheaves 54 at the sides of the main frame 1. Said chains or cables then extend inwardly to suitable actuating mech-

anism designated generally at 55 and which 40 is adapted to be operated by means of a steering wheel 56 of the usual or any preferred construction.

As shown in Fig. 3 springs 57 connect the end portions of the axle 31 with a frame 58 45 on which are disposed bearing members 59 adapted to be contacted by blocks 60 extending downwardly from the front portion of the frame 1, thus to prevent the front end of the frame from tilting to an undesirable extent relative to the axle.

What is claimed is:

A machine of the class described including a front axle, said axle having a yoke, shaft sections journalized within the axle, a 55 differential connecting the sections, an extension upon the yoke, an upstanding shaft section journalized in the extension and yoke, means for transmitting motion therefrom to the differential, a main frame, a bearing member fixedly connected thereto and bearing within the extension, a shaft within said bearing and connected by a universal joint to the upwardly extending shaft section in the extension, springs upon the end portions of the axle, a frame supported thereby, oppositely disposed bearing members on the frame, and means upon the sides of the main frame for contacting with said bearing members to limit the tilting movement of 70 the main frame relative to the axle.

In testimony that I claim the foregoing as my own, I have hereto affixed my signature in the presence of two witnesses.

McROY DE VIESE.
